UNITED STATES PATENT OFFICE.

OSCAR KATZENBERGER, OF CHICAGO, ILLINOIS.

DOUBLE-ACTING LAVATORY-HINGE.

1,138,484.

Specification of Letters Patent.

Patented May 4, 1915.

Application filed July 18, 1914. Serial No. 851,747.

To all whom it may concern:

Be it known that I, OSCAR KATZENBERGER, a citizen of the United States, and a resident of Chicago, in the county of Cook and State of Illinois, have invented a new and Improved Double-Acting Lavatory-Hinge, of which the following is a full, clear, and exact description.

This invention relates to improvements in spring hinges, and particularly to an improved double acting hinge which may be easily fitted to a door or support of any thickness.

Another object of the invention is to provide a hinge with a center having a barrel at each end arranged on one side thereof and associated with a box flange designed to connect the hinge with a support.

A further object of the invention is to simplify the entire construction of hinge whereby stamped material may be used for most of the parts and yet a strong easily operated structure presented.

In the accompanying drawings—Figure 1 is a side view of a hinge embodying the invention, the same being shown applied; Fig. 2 is a section through Fig. 1 on line 2—2; Fig. 3 is a section through Fig. 2 approximately on line 3—3; Fig. 4 is a section through Fig. 2 approximately on line 4—4; Fig. 5 is a section through Fig. 2 approximately on line 5—5; Fig. 6 is a sectional view through Fig. 1 approximately on line 6—6, the door being shown hinged to one side in dotted lines; Fig. 7 is a top plan view of the hinge with both leaves shown open, the same being shown in this position merely for the purpose of illustration; Fig. 8 is a front view of one pair of clamping members embodying certain features of the invention; Fig. 9 is a view similar to Fig. 8 showing an enlarged clamping member.

Referring to the accompanying drawings by numerals, 1 indicates a support of any desired kind, as for instance a marble slab used in the construction of a lavatory and 2 a suitable door associated with the marble slab 1.

The hinge is formed with a center 3 (Fig. 7) having barrels 4 and 5, said barrels being arranged on the same face of the center and co-acting with ears 6 and 7 on leaf 8, and with ears 9 and 10 on leaf 11. The center 3, leaves 8 and 11 and associated parts are preferably stamped from sheet metal

whereby a simple strong structure is presented. In forming the center 3 a bracing plate 12 is provided and a single sheet having the ends connected at 13 is formed with a center part 14 opposite plate 12, the opposite edges of portion 14 being formed into the barrels 4 and 5 and then the ends bent over to a position adjacent each other at line 13. Suitable rivets 15 are provided which extend through the section or portion 14 to the ends of the sheet of which portion 14 is a part, and also through the plate 12 whereby a stiff strong structure is presented defining what is known as a hinge center, which hinge center is formed with the barrels 4 and 5. The leaf 11 is intended to be the leaf connected with the door. This leaf is formed with ears 9 and 10, and with a longitudinal sector or bracing flange 16. Riveted or otherwise rigidly secured to the leaf 11 is a clamping plate 17 formed with a base 18 having upstanding flanges 19, and with a side member 20 provided with apertures for receiving clamping bolts. Associated with the side member 20 is a clamping side member 21 which is provided with grooves whereby the side member 21 may slidably fit the diverging flanges 19 as shown more particularly in Figs. 8 and 9. This provides a clamping structure for connecting the hinge to door 2. By forming this clamping structure with a base or bottom portion 17 rivets 22 will hold the parts rigidly together and will hold the door receiving clamping members centrally of the leaf 11. The leaf 8 has riveted thereto a base 23 similar to base 17, which base is provided with a side plate 24, and with diverging flanges 25 similar to diverging flanges 18. The diverging flanges 25 are adapted to accommodate a clamping side plate 26, which side plate is provided with diverging slots into which the flanges 25 project. The rivets 27 which hold the flanges 25 in position are arranged to hold the base 23 centrally of the leaf 8. The leaf 8 is provided with a partially encircling edge 28 which overlaps the barrel 4, and with a partially encircling portion 29 which overlaps part of the barrel 5.

By providing the clamping structure which includes the base 23 and associated parts means are presented which will hold the hinge centrally of a marble slab or other support, and which may be changed as shown in Figs. 8 and 9 for accommodating

different thicknesses of marble slabs or other supports. The box flange secured to the support 1 is riveted to one of the leaves, and the box flange secured to the door 2 is riveted to the other leaf. The location of these rivets may be varied during the manufacture of the hinge to fit supports and doors of any desired size, whereby the hinge will be properly centered. Figs. 8 and 9 show the same construction except that the different figures show clamping means for different sized marble slabs or doors. It is to be noted that the apertures 30 shown in these figures which receive the rivets for holding base 18 or base 23 in place are the same distance apart in each figure, and are similarly arranged so that any sized clamping means will fit any hinge. It is to be noted that by providing the flanges 25 an arrangement is presented which will take care of any irregularities, and also any slight difference in the thickness of the marble slab or door without unduly offsetting the hinge from a proper central position.

Arranged in the barrels 3 and 5 are springs and associated parts which are also connected with or engage the respective leaves for causing the same to normally remain closed and move to a closed position when forced therefrom. This construction may be of substantially any desired type, but an easily adjustable structure is disclosed in the drawing in which adjusting rings 31 and 32 are provided and bearing rings 33 and 34 are provided. The bearing rings 33 and 34 are provided with pins 35 and 36 (Fig. 3) whereby the rings 33 and 34 are rigidly connected with the leaves 8 and 11. A stop member 37 is provided beneath each of the rings 33 and 34, said stop members being formed with extensions 38 and 39, said extensions being formed with notches or slots for receiving the ends of the respective springs 40 and 41. The lower ends of springs 40 and 41 are arranged in slots or apertures of any suitable kind formed in the extensions 42 and 43 of the adjusting rings 31 and 32. The adjusting rings 31 and 32 are provided with a plurality of apertures 44 and 45 in any of which the pins 46 and 47 are inserted according to the tension of springs 40 and 41. The heads of these pins are designed to en-

gage the bracing flanges 29 and 16, respectively. The stop members 37 are provided with pins 48 and 49 whereby said members are connected with the barrels 4 and 5, respectively, and thus connect one end of the spring with the barrels 4 and 5, respectively, while the opposite ends of the springs are connected with the opposite leaves. By this construction and arrangement each leaf is held closed by an independent spring. The lower bearing washers 33' and 34' are similar to the upper bearing washers 33 and 34, and are held similarly in place by pins 48' and 49'. By this construction and arrangement it will be noticed that when the door is swung in one direction the weight is on one of the upper washers, and when the door is swung in the opposite direction the weight is on one of the lower washers.

What I claim is—

1. In a double acting hinge of the character described, a pair of leaves, each leaf being provided with a pair of turned-over ears, a center formed with a pair of barrels, said barrels being arranged on the same face of the center and adapted to fit between the respective ears set forth, a pintle extending through each pair of said ears and respective barrels, a spring arranged in each of said barrels, and means for connecting the opposite ends of each of said springs to the respective leaves and to said center so as to urge each leaf toward said center.

2. In a double acting hinge of the character described, a pair of box flanges, a leaf rigidly secured to each of said flanges, each of said leaves being formed with a pair of ears, a center formed with a pair of barrels on one side, whereby the opposite side is flat, said barrels being positioned between said ears, a pintle extending through each pair of ears and the respective barrels, a spring arranged in each of said barrels, and means for connecting the opposite ends of said springs to the respective leaves and to said center so as to urge each leaf toward said center.

In testimony whereof I have signed my name to this specification in the presence of two subscribing witnesses.

OSCAR KATZENBERGER.
